UNITED STATES PATENT OFFICE.

ELI T. STARR, OF PHILADELPHIA, PA., ASSIGNOR TO JAS. W. WHITE, J.
CLARENCE WHITE, AND H. M. LEWIS, AS TRUSTEES, OF SAME PLACE.

DENTAL HAND-PIECE.

SPECIFICATION forming part of Letters Patent No. 233,708, dated October 26, 1880.

Application filed July 29, 1880. (Model.)

To all whom it may concern:

Be it known that I, ELI T. STARR, a citizen of the United States, residing in the city and county of Philadelphia, in the State of Pennsylvania, have invented certain new and useful Improvements in Dental-Engine Hand-Pieces and Tools therefor, (Case G'), of which the following is a specification.

My invention relates to dental engines of the class embodying in their structure a motive power, a flexible rotary shaft driven by said power, and a hand-piece affording bearings for a spindle-chuck, connected at its rear end with the outer or free end of said shaft, so that the operating-tool driven by said chuck may be moved freely about in different directions by the hand which grasps the hand-piece, in order to permit said tool to be directed to the point at which it is to do its work without interfering with the free transmission of the driving-power.

The object of my present invention is, first, to improve the construction of the hand-piece, so that wear of the chuck in the casing of the hand-piece may be readily compensated, and unsteady movements or wobbling of said chuck prevented without interfering with its free rotation upon its longitudinal axis; second, to improve the tool-locking devices of the spindle-chuck, so as to permit rapid and easy insertion and removal of the operating-tools in the socket of said chuck, while firmly and securely locking said tools therein against endwise movement when at work; and, third, to improve the construction of the shanks of the operating-tools, so that any wear which may occur between them and the chuck-socket may be compensated, in order to prevent all unsteady motion or lateral vibration of the tools in the socket of the chuck while at work, whereby the operations of the dentist may be performed with greater ease, nicety, and skill, with a saving of time to the operator, while avoiding all noise disagreeable to the patient.

The subject-matter claimed is recited at the close of the specification.

The accompanying drawings represent my present improvements as embodied and organized in the best way now known to me. It

will be understood that some of my improvements may be used without the others.

In said drawings, Figure 1 is a longitudinal central section through the hand-piece casing and front end of the spindle-chuck mounted therein, on an enlarged scale, to show the entire apparatus. Figs. 2, 3, and 4 are, respectively, transverse sections through the hand-piece on the lines 2 2, 3 3, and 4 4 of Fig. 1; and Fig. 5 is a view, in elevation, of a dental operating-tool constructed according to my invention and adapted to be inserted in and driven by the spindle-chuck shown in Fig. 1.

The hand-piece casing A is shown in this example as constructed of four tubular sections—that is, it is shown as consisting of a handle-section, a, having a detachable hard-metal nose, which gives bearing to and envelops the front end of the spindle-chuck B; of a section, a', connected with the handle-section by screw-threads, so as to be removable, and affording the bearing for the rear end of the spindle-chuck; of a section, a², which is connected with the butt-end of section a' by screw-threads, so as to permit disconnection of said sections a' a², to permit access to the adjustable collar b on the rear end of the spindle-chuck, and of a shank-section, a³, which is connected with the section a² by a swivel-joint, a⁴, of well-known construction, in order to permit the handle-section, which is grasped by the hand, (being ordinarily held centrally of the fingers and thumb of the operator, somewhat after the fashion of holding a pen or pencil,) to be turned relatively to said shank-section around the spindle-chuck, so as to conform to the turning movements of the operator's hand in manipulating the tool.

The shank-section a³ is connected with the outer or free end of a flexible sheath or tube of well-known construction, while the butt-end of the spindle tool-holder or chuck B is connected in the usual way with the outer or free end of a flexible driving-shaft or power-conveyer enveloped by the before-mentioned sheath or tube, the inner end of said flexible shaft being connected with a driven spindle of the engine to receive motion therefrom, so as to impart a rapid revolving motion to the

spindle-chuck in its bearings in the hand-piece casing. The said flexible shaft and its flexible enveloping-sheath may be similar to those shown in Letters Patent heretofore granted to me September 2, 1879, and November 25, 1879, numbered, respectively, 219,320 and 222,093; but as neither they nor the particular organization of engine used constitute the subject-matter claimed by me herein, it is unnecessary to illustrate them in the drawings or describe them here in detail.

The front end of the chuck B is socketed, as usual, and is reduced in size, and has its bearing in the nose of the handle-section *a* of the casing A, while the rear end of the chuck is extended through the section *a'*, so as to have its rear bearing therein. An annular collar or ring, *b*, is fitted to and fastened upon the end of the spindle-chuck by a set-screw, preferably, so as to abut against the annular shoulder formed by the butt-end of the section *a'* of the casing, and it constitutes the pull-bearing of the chuck—that is, it constitutes a bearing which prevents the endwise forward movement of the chuck in the casing when a pulling or draw cut is being made with the tool. A similar collar, *b'*, is screwed upon a male screw, *b²*, formed upon the spindle-chuck in front of the front end of the said casing-section *a'*, so as to be adjustable, (it being fastened when adjusted by a set-screw preferably,) and it constitutes the thrust-bearing of the chuck—that is, it constitutes a bearing which prevents the endwise backward or inward movement of the chuck in the casing when a thrust or pushing cut is being made with the tool, whereby it will be seen that no endwise movement of the chuck in the casing can take place, while, as wear occurs between the parts, it can be taken up or compensated for by the adjustment of the collars above described. The said collars are made detachable as well as adjustable, so as to be readily renewed when required.

Interposed between the fixed thrust collar or bearing *b'* and the casing-section *a'* is a hard-metal loose supplemental conical friction thrust-bearing, *b³*, the conical or tapering end of which fits a similar seat in the front end of said casing-section *a'*, as clearly shown in Fig. 1. The said hard-metal conical bearing *b³* affords a plain annular shoulder in front for the collar *b'* to work against, while the conical portion of said bearing fits the casing-section *a'* and prevents wear of said section, being prevented from turning with the chuck by the friction between its conical end and said case-section.

By the employment of the loose supplemental hard-metal conical thrust-bearing *b³* not only is wear of the soft-metal casing-section *a'* prevented, but the ready substitution of a new bearing in place of one which has become worn upon its front face is also permitted. This avoids the necessity, in order to prevent wear and permit renewal of the worn parts, of such a construction as is shown, for exam-

ple, in Johnston and Browne's patent of March 25, 1879, which exhibits the casing-section as provided with a fixed steel face, a loose friction-ring being interposed between said face and the thrust-bearing or collar of the chuck to receive the thrust and friction when a pushing cut is being made with the operating-tool.

It will be noticed that a chamber, *c*, is formed between the front end of the spindle-chuck and the end of the casing-nose, through which the tool-shank is inserted, and this is for the purpose of arresting the passage into the front bearing and chuck-socket of saliva, grit, &c., when taken up by the revolution of the tool, and, furthermore, to prevent the exudation of oil from the front bearing to soil the fingers of the operator or face of the patient; but as this is the invention of Dr. T. S. Phillips, patented September 23, 1879, it, of course, forms no part of the invention claimed by me.

The shank of the operating-tool D, adapted to my improved hand-piece, as organized in the present instance, is provided with a straight cylindrical bearing portion, *d*, terminating in rear in a shoulder, *d'*, (preferably a round shoulder,) and with a reduced portion, *d²*, having an annular concave groove, notch, or recess, *d³*, with which the tool-locking devices engage, as will be fully explained.

The portion *d⁴* of the tool-shank in front of the cylindrical portion *d* is preferably reduced in size as compared with said cylindrical portion, and terminates at the front end in the cutting-burr, drill, or other operating-point *d⁵*, commonly employed for dental operations.

In practice I contemplate constructing the operating-tool either in a single piece, as has heretofore been customary, or in sections, one section consisting of the portions *d* *d'* *d²* and the other section of the operating-point *d⁵*, with a short shank or extension, *d⁴*, fitting a socket in the front end of the cylindrical portion *d*, as shown in section in Fig. 1, the two sections of the tool being rigidly united in any suitable way—for instance, by a transverse pin, *d⁶*, as shown in Figs. 1 and 5. The inner end of the cylindrical portion *d* of the tool-shank—in this instance commencing at the round shoulder *d'*—is provided with a spiral groove, *d⁷*, with which a lip, lug, or projection, *e*, in the mouth of the socket of the spindle-chuck engages when the tool is inserted in said socket and turned in the proper direction, as shown in Figs. 1 and 2, the object of which is to fasten the tool in the chuck securely against lateral movement and to compensate or take up any wear that may occur between the tool and socket.

The cylindrical portion of the tool, it will be seen, fits snugly the mouth of the chuck-socket as well as the opening in the nose of the hand-piece casing, through which the tool-shank is inserted into said socket, so that said cylindrical portion of the tool has a bearing to support it in advance of the chuck.

The tool is locked from turning in the socket

when inserted therein, and its groove engaged by the lip or projection *e* by tool-locking devices, which prevent endwise movement of the tool.

5 The devices are shown as consisting of two plate or flat springs, *E E*, fastened at their rear ends directly opposite each other in longitudinal recesses in the chuck, and having a tendency at their front ends to move outward or laterally when not compressed by a sleeve or thimble, *F*, surrounding the chuck and movable endwise thereon.

The front ends of each of the laterally-movable locking-springs is provided with a lug projecting into a lateral opening intersecting the bore or socket of the chuck, and each of said lugs is concave on its inner face, to encircle and fit, when compressed, the concave groove or notch in the tool-shank. Said sleeve 15 *F* is thrust forward to compress the lug-nosed tool-locking ends of the springs *E E* by means of a coiled spring, *E'*, also surrounding the chuck, and compressed between the fixed collar *b'* at rear and the annular shoulder formed 20 by the butt-end of the sleeve at front, the force of this spring *E'* being exerted at all times to thrust the sleeve forward to compress the laterally-yielding locking devices into engagement with the groove or notch of the tool- 25 shank, as clearly shown in Fig. 1.

It will be obvious, therefore, that when a tool is inserted in the socket and it is desired to withdraw it, the sleeve *F* must be retracted against the force of spring *E'*, so as to 30 permit the locking ends of the springs *E E* to move outward, which enables the tool to be turned and moved endwise, and this retraction of the sleeve I accomplish by means of a lever or finger-piece, *G*, pivoted to or between 35 suitable lugs on the exterior of the casing, the front end of the lever being provided with a lip or extended end, *g*, which works through 40 an opening, *f*, in the side of the casing, and engages, when the rear end of the lever is raised, with an annular shoulder, *f'*, on the 45 sleeve, to retract it as the lip *g* of the lever moves backward around the pivot of the lever.

A light plate-spring, *g'*, is fastened to the casing and acts upon a cam-edge of the lever, 50 to hold it down closely to the casing and maintain it in a position with its lip *g* out of the way of the sleeve *F*, so as not to interfere with the turning movements of said sleeve with the spindle-chuck which it surrounds when the 55 tool is at work.

It will be noticed that I have so organized the lever *G*, which actuates the tool-locking devices, that it is raised in a forward direction and moves the controlling-sleeve *F* backward 60 to permit the tool-locking devices to move laterally to release the tool, and this capacity of the lever to be lifted or moved forward to operate the tool-locking devices is a very valuable one in the manipulation of a dental-engine hand-piece, rendering its operation easy 65 and rapid, enabling the thumb or finger of

the hand that holds the hand-piece to be used to work the lever, while the other hand is at the same time free to remove or insert the tool.

It will also be noticed that I have so organized an external pivoted or rocking lever with a hand-piece to manipulate the tool-locking devices as not to interfere with the ready disconnection or removal of the handle-section of 75 the casing, in order to expose the chuck-bearings for oiling, it being unnecessary, in other words, to first remove the lever *G* in order to gain access to the chuck-bearings to clean or oil them.

In an application filed by me August 16, 1880, I have shown and claimed an operating-tool having a shoulder to determine its extent of movement into a tool-holder socket and a locking-notch at its driving end provided with a tapering rear wall. In said application I have also shown and claimed a dental-engine hand-piece provided with a socketed spindle tool-holder having a seat or enlarged mouth for the reception of a shoulder on the 90 shank of an operating-tool, and with a tool-locking device capable of moving laterally, only having a tapering lug to engage the tool-shank to lock said shank in the socket while exerting a drawing action, so as to force the 95 shoulder of the tool firmly in its seat in the tool-holder. In so far, therefore, as these specific constructions of tool and hand-piece may be said to be shown in this present case, I disclaim them herein in favor of my said application of 100 August 16, 1880, reserving, however, as the subject-matter of this case all other patentable subject-matter common to the two applications.

I claim as my invention—

1. The combination, substantially as hereinbefore set forth, of the sectional casing, the spindle-chuck, the respective adjustable collars constituting the pull and thrust bearings of the chuck, and the loose conical supplemental thrust-bearing fitting a correspondingly-formed seat in the casing.

2. The combination, substantially as hereinbefore set forth, of the hand-piece casing having a detachable handle-section, the spindle-chuck, the tool-locking devices carried by said chuck, and a lever pivoted externally on the casing and operating through an opening therein to move the tool-lock, while capable of being rocked upon its pivot, so as not to afford any obstruction to the ready removal of said handle-section.

3. The combination, substantially as hereinbefore set forth, of the casing, the spindle-chuck, a laterally-movable tool-locking device 125 carried by said chuck, the sleeve to compress said locking device, the spring acting to thrust said sleeve forward, and a lever pivoted externally on the casing and engaging said sleeve to move it in a backward direction, 130 to permit said locking device to move laterally to release the tool, while capable of being

rocked upon its pivot out of contact with said sleeve, so as to offer no obstruction to the free revolution of the chuck.

4. The combination, substantially as hereinbefore set forth, of the casing, the rotary spindle-chuck, two laterally-moving devices carried by said spindle-chuck and arranged so as to operate upon the tool-shank from opposite sides, the endwise movable sleeve, the 10 spring acting upon said sleeve to thrust it forward to compress said locking devices, and the pivoted lever to retract said sleeve to permit of the removal or insertion of an operating-tool.

15 5. An operating-tool constructed, substantially as hereinbefore set forth, with a straight cylindrical bearing portion terminating in a shoulder, and a reduced portion in rear of said cylindrical portion provided with a locking 20 groove or notch.

6. An operating-tool constructed, substantially as hereinbefore set forth, with a spiral groove, and with a separate locking notch or recess for the engagement of the tool-locking devices of a rotary chuck.

7. The combination, substantially as hereinbefore set forth, of the rotary chuck, the lip or projection in the socket thereof, the tool-locking devices of said chuck, and an operating-tool having a spiral groove for the engagement of said lip in the chuck-socket, and a notch or groove for the engagement of said tool-locking devices.

In testimony whereof I have hereunto subscribed my name.

ELI T. STARR.
